UNITED STATES PATENT OFFICE.

DANIEL EVAN ROGERS, OF BIRMINGHAM, ENGLAND, ASSIGNOR TO VERITYS LIMITED,
OF ASTON, BIRMINGHAM, ENGLAND, A BRITISH COMPANY.

OSCILLATING FAN.

Application filed November 3, 1923. Serial No. 672,646.

To all whom it may concern:

Be it known that I, DANIEL EVAN ROGERS, a subject of the King of Great Britain, residing at Plume and Victoria Works, 5 Plume Street, Aston, Birmingham, England, electrical engineer, have invented certain new and useful Improvements in Oscillating Fans, of which the following is a specification.

- 10 It has heretofore been proposed to construct an oscillating fan wherein the fan wheel is automatically oscillated about two axes substantially at right-angles to one another by the rotation of the fan wheel shaft, 15 using for the purpose a circular undulating rack with which a driving pinion gears and a link jointedly connecting a stationary carrier or base to a crank plate which is driven from the fan wheel shaft. 20 This invention relates to an oscillating fan of the type just referred to wherein combined oscillations are effected by a combination of parts comprising a crank pin driven from the fan wheel shaft, and a connecting rod and a link or equivalent parts, 25 whereby said crank pin is jointedly connected to a stationary carrier bracket of the fan and to a frame or part which can oscillate on said bracket and on which frame or part the fan wheel can oscillate. When 30 the fan wheel shaft revolves the mechanism imparts to the fan wheel a sort of continuous gyratory motion, swinging the fan wheel simultaneously up and down and sideways. 35

The mechanism of the invention is of a very simple character, and is particularly suitable to the particular type of electrically driven fan now so extensively used 40 wherein the motor casing is mounted upon trunnions of a bifurcated frame, which in turn is pivotedly mounted upon a fixed bracket or pedestal, and a single connecting rod and a single link serve to jointedly connect the crank pin to the carrier bracket and to the oscillating frame or part. 45

The motor casing is left free to rock upon its trunnions, and the frame is left free to partly revolve within the bracket or pedestal. 50 A worm carried by the fan wheel shaft drives, through a worm wheel, a small shaft to which a crank plate is attached, which small shaft may be provided with a hand operated clutch to disconnect the oscillating mechanism from the fan wheel 55

shaft. A connecting rod is universally pivoted at one of its ends to the crank pin and at its other end to a plate or arm connected to the pivoting peg of the bracket or pedestal. Upon this peg the bifurcated 60 frame is mounted to partly revolve or oscillate. A link jointedly connects a peg of the bifurcated frame with the connecting rod at a point near the crank plate.

A friction clutch is provided between the 65 crank plate and the fan wheel shaft so that if the oscillations of the fan wheel are forcibly stopped by any outside agency the mechanism will not be damaged, but will immediately pick up again when the fan wheel 70 is released, and it is preferable to conceal this clutch within the crank plate itself.

The connection between the crank pin and the crank plate is preferably made adjustable in order that the extent of oscillation 75 of the fan wheel in making its substantially gyratory oscillating movements may be adjusted.

The pegs of the bracket or pedestal and 80 of the bifurcated frame to which the connecting rod and link are attached are preferably disposed within the bifurcation of the frame.

The accompanying drawings show the invention, in its most desirable form, applied 85 to a well known type of electrically driven oscillating fan.

Fig. 1 is a side elevation, partly in section.

Fig. 2 is a rear elevation, also partly in section.

Fig. 3 is a plan view, partly in section, showing the clutch associated with the crank plate, the manner in which the crank pin is adjusted on the crank plate, and the connections between the crank pin and the pedestal and between the crank pin and the frame which supports the motor casing. 95

Fig. 4 is a detail representing how the connection between the crank pin and the 100 crank plate is adjusted to vary the amount of oscillation of the fan wheel.

The casing *a*, within which the electric motor is fitted and through which the fan wheel shaft *c* extends, is substantially of the 105 usual construction, being mounted to rock freely upon trunnions *d*, *d* having bearings within the branches *e*², *e*³ of a bifurcated frame *e* which is arranged for part revolution upon a stationary bracket or pedestal, 110

f. f^2 is a rigid peg rising from the bracket or pedestal f , over which the bifurcated frame e is mounted and supported to freely partly revolve on an antifriction bearing, 5 such as a ball bearing f^3 .

Rigidly attached to the rear end of the fan wheel shaft c is a worm g which revolves concentrically with said shaft, within a lateral extension a^2 of the casing a is 10 mounted a worm wheel h which gears with the worm and drive a small shaft h^2 which, by a reducing toothed gear, h^3 , h^4 , revolves a crank plate i revolubly carried by the extension a^2 of the casing a . To the crank pin 15 i^2 of this crank plate is jointedly connected one end j^2 of a connecting rod j , whose other end j^3 is jointedly connected to an up-standing peg l^2 of an attachment plate l fixed to the stationary upright peg f^2 of the 20 bracket or pedestal f . The jointings of this connecting rod to the crank pin i^2 and to the peg l^2 are of such a character as to provide substantially universal joints at the ends of the connecting rod. The peg l^2 is 25 always stationary, that is to say its position is constant, and it forms the principal abutment from which the oscillating movements of the fan wheel are forced.

m is a link jointedly connected at its one 30 end m^2 to the connecting rod j near the crank plate, and jointedly connected at its other end m^3 to a peg n extending upwardly from the base of the bifurcated frame e , the jointings of this link to the peg n and to the 35 connecting rod j being such as to provide substantially universal joints at the ends of the said link.

The peg n is a fixture on the bifurcated frame e and always moves therewith, and 40 its position is set off from the axis of swing of the bifurcated frame upon the peg f^2 .

In action, as the crank plate i is revolved from the fan wheel shaft, the connecting rod j automatically partly revolves the bifurcated frame e about the peg f^2 , to thereby 45 oscillate the fan wheel in one direction, while the connecting rod m compels the swing of the casing a within the frame e upon the trunnions d , d , to thereby oscillate 50 the fan wheel in a direction at a right angle to the rotation on the peg f^2 , but these two directions of oscillation are so combined by the co-action of the connecting rod and link as to impart to the fan wheel an oscillating 55 movement of a substantially gyratory character, that is to say, combined oscillation in both directions simultaneously.

A friction clutch between the crank plate i and the fan wheel shaft c is provided in 60 connection with an enlargement o^2 of the crank plate shaft o . This clutch may be in the form of a small ball q working in a radial bore of the crank plate i and a coiled spring q^2 behind said ball to cause the ball 65 to enter a semi-spherical depression c^3 in

the enlarged part o^2 of the shaft o . If through any cause the casing a is held against oscillation in its frame or said frame is held against rotation on the pedestal, the ball q is forced out of the depression 70 of the shaft o so that said shaft may revolve against the ball pressure by overcoming said pressure. The spring q^2 is backed up by the adjustable screw q^3 , so that its pressure on the ball may be adjusted. This clutch 75 is concealed within the thickness of the crank plate. Any other suitable form of clutch may be fitted to allow of the rotation of the crank plate being forcibly stopped, if oscillation of the fan wheel is accidentally 80 prevented.

The crank pin i^2 is adjustable as to throw. Its head i^3 engages a T-sectioned radial slot i^4 in the crank plate (Figs. 3 and 4), along which slot said pin is adjustable and may 85 be clamped in adjusted position by a screw-nut i^5 , which clamping does not affect the free rocking of the end of the connecting rod j on said crank pin.

A hand-operated member r is slidably 90 mounted upon an extension, r^2 of the shaft h^2 and is keyed to said extension. The worm wheel h is loosely mounted on the shaft h^2 . This member r can slide upon the extension r^2 to the limit of the space r^3 , and upon its 95 underside carries rigid pegs r^4 to engage two of a number of corresponding sinkings in the upper face of the worm wheel h , so that said worm wheel only drives the shaft h^2 through the member r , which slides friction-tight 100 upon the shaft extension. When the member r is actuated to disengage the pegs therefrom the worm wheel h the worm wheel 105 revolves freely on the shaft h^2 without imparting motion to the shaft, so that by said disengagement the oscillating movements of the fan can be stopped.

The essential features of the invention, 110 hereinafter specifically defined in the claims, are the combination with a crank pin driven by the fan wheel shaft of the connecting rod j and the link m , or equivalent parts, whereby said crank pin is jointedly connected to the stationary carrier bracket f and to the 115 frame or part e which can oscillate on said bracket and on which frame or part the fan wheel can also oscillate, and it will be understood that in the carrying out of these features various changes in detail construction 120 may be necessary all within the spirit of the invention.

Having now described my invention what I claim and desire to secure by Letters Patent is:—

1. An electrically driven oscillating fan, 125 comprising a pedestal, a frame mounted for partial rotation on said pedestal, a casing mounted to rock in said frame on an axis at an angle to the axis of rotation of said frame on said pedestal, a fan shaft rotating 130

- in said casing, a crank rotated by said fan shaft, a link having one of its ends connected to said crank and its other end connected to said pedestal at a point eccentric to the axis 5 about which said frame partially rotates on said pedestal and means connecting said crank to said frame at a point eccentric to the axis of rotation of said frame on said pedestal.
- 10 2. An electrically driven oscillating fan according to claim 1, wherein the connection between the crank and the frame comprises a link having one of its ends pivotally connected to the frame at a point eccentric to the axis of rotation of said frame on the pedestal and having its other end pivotally connected to the other link.
- 15 3. An electrically driven oscillating fan according to Claim 1, wherein the means 20 for rotating the crank from the fan shaft comprises a worm on said fan shaft, a counter shaft associated with said crank and adapted to drive the latter, a worm wheel loosely mounted on said counter-shaft and engaging said worm, and manually operable 25 means for locking said worm wheel to and releasing it from said counter-shaft.
4. An electrically driven oscillating fan, comprising a pedestal, a frame mounted for partial rotation on said pedestal, a casing 30 mounted to rock in said frame on an axis at an angle to the axis of rotation of said frame on said pedestal, a fan shaft rotating in said casing, a rotatable disc driven by said fan shaft, a crank pin adjustable radially of 35 said disc, and links connecting said crank pin to said frame at a point eccentric to its axis of ratation on said pedestal and to said pedestal eccentrically of the axis of rotation of said frame on the pedestal, respectively.

In testimony whereof I have hereunto set my hand in presence of two subscribing witnesses.

DANIEL EVAN ROGERS.
